(57) **CLAIM**

The ornamental design for a baby carrier, as shown and described.

DESCRIPTION

1. Baby carrier

1.1 is a front perspective view of a baby carrier showing the new design;

1.2 is a front elevation view thereof;

1.3 is a rear elevation view thereof;

1.4 is a left side elevation view thereof;

1.5 is a right side view elevation thereof;

1.6 is a top plan view thereof; and

1.7 is a bottom plan view thereof.

The stipple shading and line shading depict contrasting materials. The broken lines in the drawings depict decorative stitching and forms part of the claimed design.

1 Claim, 7 Drawing Sheets(56)
